UNITED STATES PATENT OFFICE.

HUGO CASSIRER, OF CHARLOTTENBURG, GERMANY.

MACHINE FOR MAKING DRESS-SHIELDS OF INDIA-RUBBER.

1,025,122.

Specification of Letters Patent.

Patented May 7, 1912.

Application filed October 26, 1910. Serial No. 589,237.

To all whom it may concern:

Be it known that I, HUGO CASSIRER, a citizen of the German Empire, residing at Charlottenburg, in the Kingdom of Prussia, 5 German Empire, have invented new and useful Improvements in Machines for Making Dress-Shields of India-Rubber, of which the following is a specification.

The present invention relates to an arrangement for manufacturing dress shields of india-rubber. Such dress shields are limited by two curves transecting each other—one concave and one convex curve. Each shield consists of two such india-rubber 10 leaves placed one on top of the other and secured to each other along the concave curve (the arm hole curve). For manufacturing such dress shields hitherto a large number of sheets of india-rubber were arranged in a pile and the single leaves were then cut out with a knife passed along a templet or punched out by means of a suitably shaped die. The convex curve thereby received at once its proper shape, while on the concave 15 side the leaves thus cut out were left a certain piece wider. In consequence of such cutting or stamping operation the single leaves would slightly stick to each other. The leaves had therefore to be subsequently 20 separated, always two at a time. Then these leaves, which still adhered to each other were parted at the convex curve. Then each pair of such leaves were cut by means of a heated handpress along the concave curve 25 to the proper length and shape and thereby the two leaves were simultaneously pasted together at the concave curve for the arm-hole. This tedious procedure and such expensive hand-work is avoided by the present 30 process, automatic mechanical operations being substituted therefor.

In the drawing a machine is shown as an exemplification by which the dress shields can be manufactured according to the new 35 method.

Figure 1 is a side elevation of the machine shown partly in section; Fig. 2 is a plan; Fig. 3 is a cross section along A—B in Fig. 1 (seen from the right); Fig. 4 is a 40 cross section along C—D in Fig. 1 (seen from the right).

The machine operates in the following manner: Two lengths of india-rubber cut to the necessary width and wound up in 45 rolls are placed on two spindles a , a^1 which

are supported in such a manner on swinging holders b , b^1 fitted to the machine frame v , that they may be either rested against or raised from an endless belt conveyer c traveling over guide drums c^1 , c^2 arranged 50 at the ends of the frame v . The lengths of india-rubber are now intermittently advanced by means of the belt conveyer c . Between each two successive advances there is a stoppage of some length, during which 55 at one point of the machine, the arm hole curve f is punched out and at the same time the two pieces of india-rubber are pasted together along this curve, and at another point of the machine (following in the direction of travel of the material) the convex curve g is cut out. All movements are produced by a shaft h , which is arranged on the one side of the machine and which is driven by means of a chain wheel h^1 or in 60 any other suitable manner. The intermittent motion of the conveyer belt c together with the india-rubber material on it is produced by the intermittent rotation of drum c^2 . Shaft h drives by means of bevel gears 65 h^2 , h^3 of equal size a shaft i at the same speed. At each revolution of shaft i a pin i^1 turns, in known manner during part of such revolution, a Maltese cross k by one 70 division. During the remainder of each 75 revolution of shaft i , the Maltese cross k is prevented by disk i^2 from turning any farther. The spindle k^1 of the Maltese cross drives by means of change wheels k^2 , k^3 , k^4 , k^5 the drum c^2 . The change wheels 80 are so adjusted with relation to each other, that the length of the arc through which the drum c^2 is rotated and thus also the distance the belt c and the india-rubber material 85 on it are advanced, are regulated as may be 90 desired. The india-rubber strips are therefore advanced at each revolution of the shaft h a certain distance and then remain stationary for a certain length of time. The 95 conveyer belt c and the india-rubber on the 100 same are heated during part of their travel by means of plate c^3 heated by Bunsen burners.

The punch e for cutting out the arm hole curve is arranged vertically adjustable in an 105 upright frame d ; said punch consisting of a steel blade ground at its lower edge to a cutting edge, and is adjusted before starting of the machine by suitably provided means to the armhole curve required. The spindle e^1 110

carrying the cutter e is vertically moved by means of double armed levers l (Fig. 4) which are arranged to swivel at l^1 on frame d . The left ends of said levers l engage like a fork the pins e^2 fitted in spindle e^1 . The right hand ends of levers l are pressed upward by means of a spring l^2 . On shaft h is fitted an eccentric h^4 , which will move rod h^5 up and down at each revolution of shaft h . At the other end of rod h^5 a stop h^6 is adjustably arranged. In Fig. 4 the rod h^5 is shown in its highest position. If shaft h is turned and in consequence thereof the eccentric h^4 lowers rod h^5 , the stop h^6 will abut against the right arm of levers l and force the same downward contrary to the action of springs l^2 . In a corresponding manner rod e^2 and punching cutter e will be raised. It thus depends on the adjustment of stop h^6 during what part of a revolution of shaft h the cutter e is raised. During the remaining part of each revolution the cutter e is pressed down against the india-rubber strips below it, the force of such downward pressure depending on the strength of spring l^2 . The stop h^6 is so adjusted, that the cutter e remains raised during the advance of the india-rubber. When such advance has been completed, the cutter e is lowered and will only be raised again shortly before the next advance of the india-rubber commences. The cutter e thus remains pressed against the india-rubber strips for some length of time and with a constant pressure. The cutting edge of the punch e is sharp enough to cut right through both layers of india-rubber along the predetermined curve. The one of the bevels forming the cutting edge of said punch e , namely the one toward the piece to be cut out, is not steeply inclined but somewhat more obtuse, so that the cutter will, when it is in its lowest position, exert with this bevel a permanent pressure against a narrow strip of the material along the curve cut. The heating of the india-rubber, produced by the heating arrangement c^3 , the pressure of the cutter, caused by the spring l^2 and the bevel of the cutting edge are so chosen that within the space of time available the two pieces of india-rubber will be made to securely adhere to each other along the armhole curve. In such a manner the armhole curves f are cut out successively at suitable distances from each other (Fig. 2).

For cutting out the convex curve g the following arrangement is provided: The cutting out is effected by means of a disk cutter m with a very sharp cutting edge, which is pressed against the india-rubber during the stoppage of the same, and rolls along the convex curve to be cut out. The cutter is rolled at one operation along the curve in one direction and at the next stoppage in the opposite direction. Having cut

at each of these travels the india-rubber along the convex curve g it is automatically raised and remains in such raised position until the belt conveyer c and with the latter the thereon lying india-rubber strips have been moved along, whereupon the cutter is again lowered and now travels back in the opposite direction, thereby cutting a fresh curve into the india-rubber, being again automatically raised at the opposite end. The disk cutter m is preferably heated (say by means of electricity or by a blue flame burner traveling together with cutter m) to a very high temperature. (The arrangement for heating the disk cutter m is not shown in the drawing.) In consequence of the sharp edge of the disk cutter m , its high temperature and the fact, that it stops at no point of the cut curve, traveling on the contrary comparatively rapidly along the curve, the two pieces of india-rubber are cut sharply through along said curve. The pieces inclosed by curves f and g now represent the finished, cut out dress shields which adhere to each other along the armhole curves f . At the further advance of the conveyer belt c they are moved as far as the drum c^2 where they are taken off by an attendant. This attendant also removes the remainder of the india-rubber strips from the conveyer belt. While returning from drum c^2 to drum c^1 the conveyer belt may then be completely cleaned by means of a revolving brush not shown in the drawing.

In the constructional form shown in the drawings the movement of the circular cutter m is produced by the following means: On shaft h is fitted a gear wheel h^7 which meshes with a gear wheel n of twice the size. Coupled to gear wheel n is a grooved cam disk n^1 . Into the groove of said cam disk n^1 engages a pin o , which is fitted into the right hand end of a double armed lever o^1 arranged to swivel on the machine frame. The groove in the cam disk n^1 consists of a circular section, concentric with the cam disk itself, an outer circular section, likewise concentric to the cam disk and two intermediate curved sections connecting said inner and outer sections. At one complete revolution of the cam disk n^1 the pin o is thus at one time held for a while at its innermost position, then moved toward outside and there held for a while and finally moved inwardly again. As the cam disk n^1 revolves only half as fast as the shaft h , the pin o will during one revolution of shaft h be held in its one terminal position and moved into the opposite terminal position, and during the next revolution of shaft h the pin will be held in the opposite terminal position and be then moved back into the former one. The other end of the double armed lever o^1 (Fig. 3) is linked by an in-

- termediate member o^2 to arm p^1 of a bevel gear sector p , which is rotatably fitted at p^2 in a standard q . Said bevel gear sector p meshes with a bevel gear r which is likewise 5 rotatably arranged in the standard q (Figs. 1 and 2). Coupled to bevel gear r is a gear wheel sector r^1 , meshing with a pinion s . The pinion s with its spindle s^1 are likewise rotatably fitted in standard q . Spindle s^1 10 is provided with a guide s^2 in which a prismatic arm m^2 of the cutter holder m^1 is slideable. The cutter holder m^1 carries two rollers m^3 and is drawn by two springs m^4 with these rollers m^3 against a curve section q^1 . 15 The said curve section q^1 is exchangeably fitted to standard q . Correspondingly to the reciprocation of the pin o in consequence of the rotation of cam disk n^1 also the bevel gear sector p will be reciprocated. 20 In consequence thereof the pinion s and the spindle s^1 are rotated in one or the other direction. At such rotation the cutter holder m^1 will follow with its rollers m^3 the curve disk q^1 . Said curve disk q^1 has such a 25 shape, that the cutter m is moved along the desired curve g . The cutter m is rotatably fitted in a fork m^5 . The fork m^5 is vertically slideable with a rod m^6 in cutter holder m^1 . A spring m^7 tends to force the fork m^5 down, thus press the cutter m against the india-rubber material. The upper end 30 of rod m^6 projecting beyond the cutter holder m^1 carries an arm m^8 . At the end of the oscillating motion, which the cutter 35 holder receives (both in one and the other direction of oscillation) the arm m^8 will roll upon a lug q^2 , one of which is provided at each end of the curve disk q^1 . Heréby arm m^8 and rod m^6 are raised contrary to the 40 action of spring m^7 and the cutter m is thereby lifted from the india-rubber material. At each revolution of the driving shaft h therefore the cutter (by the arm m^8 rolling off from the lug q^2) is pressed into 45 the india-rubber strips. The cutter m is then swung along in the one direction and cuts the curve g and is again lifted at the far end of its travel. Now the india-rubber strips are advanced, the cutter m is again 50 lowered and now cuts the following curve g traveling this time in the opposite direction. As the curve disk q^1 is arranged in such a manner, that it can be easily exchanged, any 55 desired curve g may be cut by employing a corresponding curve disk. For safeguarding that the curve g cut has the correct position to the curve f cut, so that the dress shield cut receives the desired width, the standard q is adjustably arranged. In the 60 constructional form shown the standard q is provided with a rack q^3 on its lower surface. The standard q is adjusted by the turning of a pinion q^4 engaging in said rack q^3 . 65 By means of the hereinbefore described
- machine, dress shields may be automatically cut from strips of india-rubber, said dress shields having any desirable form and size. These dress shields may then be immediately vulcanized, separating the two leaves 70 at the convex curve being dispensed with. By means of the hereinbefore described machine one attendant will be able to turn out within the same time about four times as many dress shields as was hitherto possible by handwork. 75
- I claim:
1. A machine for cutting dress shields from sheets of india rubber comprising means for feeding along two superposed strips, means for making a cut through both sheets for the inner or concave edge of the shield and means for heating the edges and pressing them together simultaneously with the cutting, thereby causing said edges of the partly cut out shields to adhere along 80 said cut.
  2. A machine for cutting dress shields from sheets of india rubber comprising means for feeding along two superposed strips, means for heating the strips, means for making a cut through both sheets for the inner or concave edge of the shield and means for pressing the edges simultaneously with the cutting, thereby causing said edges of the partly cut out shields to adhere along 85 the cut.
  3. A machine for cutting dress shields from sheets of india rubber comprising means for feeding along two superposed strips, a heated plate over which the strips are fed, means for making a cut through both sheets for the inner or concave edge of the shield and means for pressing the edges simultaneously with the cutting, thereby causing said edges of the partly cut out shields to adhere along 90 the cut.
  4. A machine for cutting dress shields from sheets of india rubber comprising means for feeding along two superposed strips, means for heating the strips, and means for simultaneously making a cut through both sheets for the inner or concave edge of the shield and causing said edges of the partly cut out shields to adhere along 95 the cut comprising means adjacent to the cutting edge of the cutter for pressing the two sheets together after the cut is made.
  5. A machine for cutting dress shields from sheets of india rubber comprising means for feeding along two superposed strips, means for heating the strips, means for simultaneously making a cut through both sheets for the inner or concave edge of the shield and means for causing said 100 edges of the partly cut out shields to adhere along said cut, comprising a cutter having an obtusely beveled edge, and a pressing face to engage and press upon the edges of the cut out portions. 105

6. A machine for cutting dress shields from sheets of india rubber comprising means for feeding along two superposed strips, means for heating the strips, means for simultaneously making a cut through both sheets for the inner or concave edge of the shield and causing said edges of the partly cut out shields to adhere along the cut comprising means adjacent to the cutting edges of the cutter for pressing the two sheets together after the cut is made.
7. A machine for cutting dress shields from sheets of india rubber comprising means for feeding along two superposed strips, means for heating the strips, means for simultaneously making a cut through both sheets for the inner or concave edge of the shield and causing said edges of the partly cut out shields to adhere along the cut, comprising a cutter having an obtusely beveled edge.
8. A machine for cutting dress shields from sheets of india rubber comprising means for feeding along two superposed strips, a heated plate over which the strips are fed, means for simultaneously making a cut through both sheets for the inner or concave edge of the shield and causing said edges of the partly cut out shields to adhere along said cut, comprising means adjacent to the cutting edge of the cutter for pressing the two sheets together after the cut is made.
9. A machine for cutting dress shields from sheets of india rubber comprising means for feeding along two superposed strips, a heated plate over which the strips are fed, means for simultaneously making a cut through both sheets for the inner or concave edge of the shield and causing said edges of the partly cut out shields to adhere along said cut, comprising a cutter having an obtusely beveled edge.
10. A machine for cutting dress shields from sheets of india rubber comprising a cutter for making a cut through two superposed sheets to form the inner or concave edge of a dress shield, a second cutter for making a second cut through the superposed sheets to form the outer or convex edge of a dress shield, means for heating the sheets before they reach the first cutter, means for pressing together the edges of the shield and means for feeding the superposed sheets to and beyond the cutters.
11. A machine for cutting dress shields from sheets of india rubber comprising a cutter for making a cut through two superposed sheets to form the inner or concave edge of a dress shield, a second cutter for making a second cut through the superposed sheets to form the outer or convex edge of a dress shield, means for feeding the superposed sheets to and beyond the cutters, a heated plate over which the sheets
12. A machine for cutting dress shields from sheets of india rubber comprising a cutter with an obtusely inclined edge for making a cut through two superposed sheets to form the inner or concave edge of a dress shield and pressing the cut edges together, a second cutter for making a second cut through the superposed sheets to form the outer or convex edge of a dress shield, and means for feeding the superposed sheets to and beyond the cutters.
13. A machine for cutting dress shields from sheets of india rubber comprising a cutter with an obtusely inclined edge for making a cut through two superposed sheets to form the inner or concave edge of a dress shield and pressing the cut edges together, a second cutter for making a second cut through the superposed sheets to form the outer or convex edge of a dress shield, means for feeding the superposed sheets to and beyond the cutters, and means for heating the sheets before they reach the first cutter.
14. A machine for cutting dress shields from sheets of india rubber comprising a cutter with an obtusely inclined edge for making a cut through two superposed sheets to form the inner or concave edge of a dress shield and pressing the cut edges together, a second cutter for making a second cut through the superposed sheets to form the outer or convex edge of a dress shield, means for feeding the superposed sheets to and beyond the cutters, and a heated plate over which the sheets pass before reaching the first cutter.
15. A machine for cutting dress shields from sheets of india rubber comprising a cutter for making a cut through two superposed sheets to form the inner or concave edge of a dress shield, a second cutter for making a second cut through the superposed sheets to form the outer or convex edge of a dress shield, means for feeding the superposed sheets to and beyond the cutters, and means for heating the second cutter.
16. A machine for cutting dress shields from sheets of india rubber comprising a cutter for making a cut through two superposed sheets to form the inner or concave edge of a dress shield, a second cutter for making a second cut through the superposed sheets to form the outer or convex edge of a dress shield, means for feeding the superposed sheets to and beyond the cutters, means for heating the sheets before they reach the first cutter, means for heating the second cutter, and means for pressing together the cut edges.
17. A machine for cutting dress shields from sheets of india rubber comprising a cutter for making a cut through two super-

- making a second cut through the superposed sheets to form the outer or convex edge of a dress shield, means for feeding the superposed sheets from the first cutter to the second cutter and holding them at rest during the second cutting operation, means for heating the sheets before they reach the first cutter, and means for heating the second cutter.
26. A machine for cutting dress shields from sheets of india rubber comprising a cutter with an obtusely inclined edge for making a cut through two superposed sheets to form the inner or concave edge of a dress shield and pressing the cut edges together, means for feeding the superposed sheets to the cutter and holding them at rest during the cutting, a second cutter for making a second cut through the superposed sheets to form the outer or convex edge of a dress shield, means for feeding the superposed sheets from the first cutter to the second cutter and holding them at rest during the second cutting operation, and a heated plate over which the sheets pass before reaching the first cutter.
27. A machine for cutting dress shields from sheets of india rubber comprising a cutter with an obtusely inclined edge for making a cut through two superposed sheets to form the inner or concave edge of a dress shield and pressing the cut edges together, means for feeding the superposed sheets to the cutter and holding them at rest during the cutting, a second cutter for making a second cut through the superposed sheets to form the outer or convex edge of a dress shield, means for feeding the superposed sheets from the first cutter to the second cutter and holding them at rest during the second cutting operation, a heated plate over which the sheets pass before reaching the first cutter, and means for heating the second cutter.
28. A machine for cutting dress shields from sheets of india rubber comprising a frame, a vertically reciprocable cutter mounted on the frame, a longitudinal driven shaft journaled in the frame, an eccentric on the shaft, a strap around the eccentric, a vertical bar attached to the strap, a double ended lever pivoted to the frame having one end attached to the cutter and the other end to the vertical bar, a spring on the vertical bar between the strap and the double ended lever, and an adjustable stop on the vertical bar above the double ended lever.
29. A machine for cutting dress shields from sheets of india rubber comprising a frame, a vertically reciprocating cutter, a rotary disk cutter mounted in the frame and adapted to be moved in the arc of a circle, a longitudinal driven shaft journaled in the frame, and means driven from the shaft for actuating both cutters.
30. A machine for cutting dress shields from sheets of india rubber comprising a frame, a vertically reciprocable cutter mounted on the frame, a vertical shaft journaled in bearings fixed to the frame, a longitudinal driven shaft journaled in the frame, and adapted to be moved in the arc of a circle, an eccentric and a cam grooved disk mounted on the shaft, means actuated from the eccentric for operating the reciprocating cutter and means actuated from the cam grooved disk for operating the disk cutter.
31. A machine for cutting dress shields from sheets of india rubber comprising a frame, a longitudinal driven shaft journaled in the frame, a vertical shaft journaled in bearings fixed to the frame, a cutter holder radially secured to the vertical shaft, a cutter carried by the cutter holder, and means actuated from the longitudinal shaft for oscillating the vertical shaft.
32. A machine for cutting dress shields from sheets of india rubber comprising a frame, a longitudinal driven shaft journaled to the frame, a vertical shaft journaled in bearings fixed to the frame, a cutter holder radially secured to the vertical shaft, a cutter carried by the cutter holder, a fixed curved guide spring for yieldingly holding the cutter against the guide, and means actuated from the longitudinal shaft for oscillating the vertical shaft.
33. A machine for cutting dress shields from sheets of india rubber comprising a frame, a longitudinal driven shaft journaled on the frame, a vertically reciprocable cutter mounted on the frame, a vertical shaft journaled in bearings fixed to the frame, a pinion on the vertical shaft, a horizontal pivoted gear sector engaging the pinion, a cutter holder radially secured to the vertical shaft, means actuated from the longitudinal shaft for oscillating the vertical shaft and means actuated from the longitudinal shaft for oscillating the horizontal sector.
34. A machine for cutting dress shields from sheets of india rubber comprising a frame, a longitudinal driven shaft journaled on the frame, a vertically reciprocable cutter mounted on the frame, a vertical shaft journaled in bearings fixed to the frame, a pinion on the vertical shaft, a horizontal pivoted gear sector engaging the pinion, a cutter holder radially secured to the vertical shaft, means actuated from the longitudinal shaft for oscillating the vertical shaft, means actuated from the longitudinal shaft for oscillating the horizontal sector, comprising a bevel pinion secured concentrically to the gear sector, and a vertical pivoted gear sector engaging the bevel pinion.
35. A machine for cutting dress shields from sheets of india rubber comprising a frame, a longitudinal driven shaft journaled on the frame, a vertically recipro-

cable cutter mounted on the frame, a vertical shaft journaled in bearings fixed to the frame, a pinion on the vertical shaft, a horizontal pivoted gear sector 5 engaging the pinion, a cutter holder radially secured to the vertical shaft, means actuated from the longitudinal shaft for oscillating the vertical shaft, means actuated from the longitudinal shaft for oscillating 10 the horizontal sector, comprising a bevel pinion secured concentrically to the gear sector, a vertical pivoted gear sector engaging the bevel pinion, a double ended lever centrally fulcrumed and loosely connected 15 at one end to the vertical sector, and means for oscillating the lever.

36. A machine for cutting dress shields from sheets of india rubber comprising a frame, a longitudinal driven shaft journaled 20 on the frame, a vertically reciprocable cutter mounted on the frame, a vertical shaft journaled in bearings fixed to the frame, a pinion on the vertical shaft, a horizontal pivoted gear sector 25 engaging the pinion, a cutter holder radially secured to the vertical shaft, means actuated from the longitudinal shaft for oscillating the vertical shaft, means actuated from the longitudinal shaft for oscillating 30 the horizontal sector, comprising a bevel pinion secured concentrically to the gear sector, a vertical pivoted gear sector engaging the bevel pinion, a double ended lever centrally fulcrumed 35 and loosely connected at one end to the vertical sector, a cam grooved disk on the longitudinal shaft, and a pin on the other end

of the double ended lever engaging on the cam groove.

37. A machine of the character described, comprising two rolls suitably journaled in the frame, an endless belt conveyer, means for imparting an intermittent motion thereto for feeding material in a double layer to the rolls, means for heating the material, a curved cutter, means for adjusting it to any desired curve, means for operating the cutter during the rest of the conveyer to cut through the two layers, and means operable with the cutter to press together the edges of the parts cut from the two layers. 50

38. A machine of the character described, comprising two rolls suitably journaled in the frame, an endless belt conveyer, means for imparting an intermittent motion thereto for feeding material in a double layer to the rolls, means for heating the material, a curved cutter, means for adjusting it to any desired curve, means for operating the cutter during the rest of the conveyer to cut through the two layers, and means operable 55 with the cutter to press together the edges of the parts cut from the two layers, comprising that part of the cutter adjacent to the edge, said adjacent part having its bottom at a very slight angle from the horizontal. 60

In witness whereof I have hereunto set my hand in presence of two witnesses.

HUGO CASSIRER.
